(57) **CLAIM**

The ornamental design for a signal beacon with an adapter, as shown and described.

DESCRIPTION

1. Signal beacon

2. Signal beacon with an adapter

The patent or application file contains at least one drawing executed in color. Copies of this patent or patent application publication with color drawing(s) will be provided by the Office upon request and payment of the necessary fee.

Fig. 1.1 is a perspective view of the ornamental design for a signal beacon with an adapter;

Fig. 1.2 is a front view of the ornamental design of Fig. 1.1; Fig. 1.3 is a rear view of the ornamental design of Fig. 1.1; Fig. 1.4 is a right side view of the ornamental design of Fig. 1.1;

Fig. 1.5 is a left side view of the ornamental design of Fig. 1.1;

Fig. 1.6 is a top view of the ornamental design of Fig. 1.1; Fig. 1.7 is a bottom view of the ornamental design of Fig. 1.1;

Fig. 2.1 is a perspective view of the ornamental design with the adapter;

Fig. 2.2 is a front view of the ornamental design with the adapter of Fig. 2.1;

Fig. 2.3 is a right side view of the ornamental design with the adapter of Fig. 2.1;

Fig. 2.4 is a left side view of the ornamental design with the adapter of Fig. 2.1;

Fig. 2.5 is a rear view of the ornamental design with the adapter of Fig. 2.1;

Fig. 2.6 is a top view of the ornamental design with the adapter of Fig. 2.1; and

Fig. 2.7 is a bottom view of the ornamental design with the adapter of Fig. 2.1.
